UNITED STATES PATENT OFFICE.

GEORGE R. PLOETZ, OF NEW YORK, N. Y.

DESIGN FOR A SPOON.

50,628.

Specification for Design. Patented Apr. 17, 1917.

Application filed February 9, 1917. Serial No. 147,715. Term of patent 3½ years.

To all whom it may concern:

Be it known that I, GEORGE R. PLOETZ, a subject of William II, Emperor of Germany, residing at New York, in the county of New York and State of New York, have invented a new, original, and ornamental Design for a Spoon, of which the following is a specification, reference being had to the accompanying drawings, forming part thereof.

The figure is a spoon with the ornamentation of a submarine boat for the handle of the spoon and a human head for the end of the spoon.

I claim:

The ornamental design for spoon as shown.

GEORGE R. PLOETZ.
